UNITED STATES PATENT OFFICE.

JAMES WATT, OF WESTBURY-ON-TRYM, ENGLAND, ASSIGNOR TO J. & F. POOL, LIMITED, OF HAYLE, ENGLAND.

ROTARY SCREENING APPARATUS.

Application filed February 4, 1928, Serial No. 251,951, and in Great Britain February 12, 1927.

The invention relates to rotary separators or screens of the type in which the rotary screening member is divided up into a series of separate compartments extending longitudinally from end to end thereof, and in which each compartment is divided up into a number of sections or portions with the perforations or openings in the successive sections or portions increasing in size as the 10 exit end of the rotary member is approached.

The object of the present invention is to provide improved rotary screening apparatus of this type in which a quick output is obtained and in which the finest material will 15 all pass out through the finest screen. A further object of the invention is to provide an apparatus in which the central shaft is sufficiently stiff to avoid the necessity of any bearing between its ends.

According to the present invention there are employed a plurality of compartments each consisting of screens of circular cross section and provided with perforations of 20 successively increasing size mounted in alignment and arranged around a common axis. The central shaft for carrying the screens is preferably formed by a number of arcuate plates having their concave sides outwards, which are connected together along their 25 outer edges, thereby forming a strong shaft which is adapted to receive the screens located partly within each arcuate plate. The central shaft may however be of any desired section.

The hollow shaft when made of arcuate plates in the manner stated, may be strengthened by employing strips of metal or girders between each two adjacent plates where they are connected together. The central shaft is 30 preferably provided with arcuate plates in planes transverse to the central shaft and attached thereto which form seatings for the screens.

The various portions of each screen are attached to the central shaft and preferably by means of metal straps passing around portions of the screens and bolted at their ends to the ends of the arcuate seatings carried by the central shaft. The inlet ends of the finest 40 screens may each be located within a ring attached to an end plate, which latter is suitably perforated to allow the material to enter the screens.

The arcuate seatings for the screens divide

the exterior surface of the central shaft into 55 sections, thereby preventing the materials, which have passed through one set of the screens on to the external surface of the shaft, passing down beyond the junction between the said set of screens and the adjoining 60 coarser screens. When employing a central hollow shaft made of arcuate plates connected along their edges the outer surfaces of the plates forming the hollow shaft are, when desired, protected with renewable plates. 65

The whole group of screens is so mounted that it may be rotated upon the axis of the central shaft, and this latter may be provided with a short shaft and bearing at one end and a suitable bearing surface at the other end 70 around the entrance to the receiving chamber and rollers to carry the bearing surface. The apparatus may if desired be mounted in flexible supports such as chains, and may be rotated therein in known manner and this construction is therefore not illustrated. 75

In some cases the central shaft extends slightly beyond the coarsest series of screens and is provided with a disc or plate to arrest and deliver the material which has been rejected by all the screens. 80

The invention is illustrated in the accompanying drawings in which:—

Fig. 1 is a side elevation of a complete apparatus, partly broken away and partly in 85 section, showing one method of carrying the invention into effect.

Fig. 2 is a section on the line A—B of Fig. 1, some details being omitted.

Fig. 3 is an elevation of the inlet end of 90 the apparatus, the screens being merely indicated by circles.

Fig. 4 is a section on the line C—D of Fig. 1, seen in the direction of the arrow, some parts being omitted as hereinafter explained. 95

Fig. 5 is a vertical section taken through the end of an inlet screen on the line E—F of Fig. 4.

Fig. 6 is an end elevation partly in section on the line I—J of Fig. 8, showing a modified 100 construction of apparatus.

Fig. 7 is a section on the line G—H of Fig. 6 showing some parts in elevation.

Fig. 8 is a side elevation partly in section of the parts of one end of the screening apparatus shown in Figs. 6 and 7. 105

Fig. 9 is an end elevation, partly broken away, of the parts shown in Fig. 8.

Fig. 10 is an end elevation partly in section through the main shaft showing a further modified construction of apparatus.

Fig. 11 is a side elevation of the parts 5 shown in Fig. 10.

Fig. 12 is a detail view to an enlarged scale. The rotary screening member is divided into compartments each consisting of screens 1, 2 and 3, of circular cross section mounted 10 in alignment, as shown. The screens are arranged in sets of four around a hollow shaft designated generally by the Figure 4. It will be understood that other numbers of screens may be employed in sets and the shaft 15 may be of any suitable cross section.

If desired the inlet screens 1, 1 may each be surrounded by a perforated jacket 5 forming an extra outer screen. The outer screen 5 has the smallest apertures therein, the screens 1, 1 20 have the next larger size of apertures, the screens 2, 2 have still larger apertures and the screens 3, 3 have the largest apertures. All these apertures are marked 6.

The hollow shaft 4, as shown, consists of 25 arcuate plates 7 connected together at their edges, and in the particular construction shown these edges are strengthened by inner plates or girders 8, the plates 7 and girders 8 being riveted together. Should there be any 30 other number of screens than four in a set the hollow shaft will be made of a like number of arcuate plates.

To the outer concave sides of the plates 7 are fixed the angle plates 9, shown in Figs. 1 35 and 12 but omitted in Fig. 4 for the sake of clearness, for fixing the arcuate flanged plates 10 which form seatings for the screens 1, 2, 3. These screens 1, 2, 3 intermediate of their ends are fixed upon the seatings 10 by means of 40 straps 11. The straps 11 and plates 10 have radial projections which are connected by nuts and bolts 12.

At their inlet ends the screens 1 are fastened by bands 13 which fit around the screens 45 1 and around flanged rings 14 which are fixed to a plate 15 having apertures 16 formed therein for the admission of the materials to be screened into the screens 1, 1. The plate 15 is provided with a cone 17, the two parts being fixed together by T plates 18. To the cone 17 is fixed an end plate 19 having a central aperture 20 through which the materials are fed. The end plate 19 carries an outer rim 21 which is supported by rollers 22 mounted 50 in suitable bearings and supports 23.

The outer screen 5, 5 are supported at one end by the screens 1 by means of the distance pieces 24 which are bolted to the screens 1 and at the other end by means of a distance 60 ring 25. Divided rings 26 are employed around the distance pieces 24 and distance rings 25 to secure the screens 5 to the inner screens 1.

The hollow shaft 4 is connected at the out-

let end of the apparatus to a closing plate 27 65 carrying a bevel wheel 28. Within the closing plate and bevel wheel 28 there is fixed a short shaft 29 mounted in a bearing 30 carried by a suitable support 31. As seen in Fig. 2 the bevel wheel 28 is driven by a bevel 70 pinion 32 which is mounted upon a shaft 33. The bevel pinion 32 and shaft 33 are omitted in Fig. 1.

The materials to be screened are fed 75 through the aperture 20 in the end plate 19 into the cone 17 and find their way through the apertures 16 directly into the screens 1. The finer materials escape from the screens 1 into the outer screens 5 from which the finest 80 materials escape through the apertures therein. The coarser materials which find their way into the outer screens 5 are delivered at the ends 34.

The materials which are retained by the 85 screens 1 then pass into the screens 2 and pass through the apertures therein. The materials which are retained by the screens 2 enter the screens 3 and part thereof passes out through the apertures in these last mentioned 90 screens. The remaining and larger portions of material pass out of the screens 3 at the ends 35 thereof.

The materials which pass through the apertures in the screens and which may rest 95 through part of a revolution in the concave portions of the hollow shaft 4, cannot pass the plates or seatings 10, and cannot therefore get mixed with the material passing through the next coarser screens.

On the plates 7 and intermediate of the 100 seatings 10 may be arranged thin plates 36, which can be readily renewed, to protect the plates 7. These plates 36 are shown in Figs. 1 and 4.

The modified form of apparatus shown in 105 Figs. 6, 7, 8 and 9 allows each screen 3 to be rotated upon its own axis whilst rotating together with the hollow shaft 4. This modified apparatus also allows all the screens to receive a reciprocating longitudinal movement.

The screens 3 have each fixed around its exterior a roller path 37 which is carried by 110 rollers 38 mounted in a channel ring 39 which is fixed to the hollow shaft 4. These rollers 38 not only allow the screens 3 to rotate upon their own axes but allow them to slide longitudinally.

An external gear wheel 40 is fixed to the 115 exterior of each screen 3 and it gears with a stationary internal gear wheel 41. As the shaft 4 rotates carrying with it the screens 3 these latter, due to the gearing of the wheels 40 and 41, will rotate upon their own axes.

The gear wheels 40 are each provided with 120 cams 42 against which act cam rollers 43 carried by brackets 44 fixed to the hollow shaft 4. As the screens 3 rotate on their

own axes the cams 42 will be acted upon by the cam rollers 43 and the screens 3 will be moved longitudinally in one direction.

Each screen 3 is provided in its interior with a cross piece 45, through which passes one end of a spring 46. The other end of the spring 46 passes through the closing plate 27 of the hollow shaft 4. When the screens, shown in Figs. 7 and 8, have been moved to the right by the action of the rollers 43 and cams 42, the springs 46 will return the parts towards the left after the rollers leave the cam surfaces. The ends of the springs 46 can rotate in the plates 27 and in the cross pieces 45, thereby allowing the screens 3 to rotate with respect to the hollow shaft.

Any ordinary means may be employed to decrease friction between the ends of the spring 46 and the parts 27 and 45.

It will be understood that if the cams 42 and cam rollers 43 be omitted that the screens 3 will only receive a rotary movement upon their own axes in addition to the rotary movements of the hollow shaft 4.

In the modification shown in Figs. 10 and 11 the screens 3 are provided with exterior roller paths 37 and are carried by rollers 38 and channel rings 39, as previously described, but are not provided with gear wheels 40 and there is no external gear wheel 41.

On the ends of the screens 3 are fixed brackets 47 carrying cam rollers 48 which as the shaft 4 rotates, are engaged by the cams 49 on the stationary rings 50 which move the screens 3 to the right. These screens 3 are returned to the left by springs 46 as previously described. In this construction the screens 3 merely receive a reciprocating motion in addition to the rotary motion imparted by the shaft 4.

What I claim as my invention is:—

1. An improved rotary screening apparatus having a plurality of compartments each consisting of screens of circular cross section mounted in alignment and provided with perforations of successively increasing size, a central shaft around which the screens are fixed, said central shaft being formed by a number of arcuate plates having their concave sides outwards, which are connected along their outer edges, means for delivering the materials to be screened directly into the screens having the smallest perforations at one end of the compartments, and means for supporting and driving the screens and shaft as set forth.

2. An improved rotary screening apparatus having a plurality of compartments each consisting of screens of circular cross section mounted in alignment and provided with perforations of successively increasing size, a central shaft around which the screens are fixed, said central shaft being formed by a number of arcuate plates having their con-

cave sides outwards, which are connected along their outer edges, strips of metal fixed between the edges of each two adjacent plates, means for delivering the materials to be screened directly into the screens having the smallest perforations at one end of the compartments, and means for supporting and driving the screens and shaft as set forth.

3. An improved rotary screening apparatus having a plurality of compartments each consisting of screens of circular cross section mounted in alignment and provided with perforations of successively increasing size, a central shaft around which the screens are fixed, said central shaft being formed by a number of arcuate plates having their concave sides outwards, which are connected together along their outer edges, arcuate seatings attached to said arcuate plates and acting as seatings for the said screens, metal straps passing around portions of the screens and bolted at their ends to the ends of the arcuate seatings, means for delivering the materials to be screened directly into the screens having the smallest perforations at one end of the compartments, and means for supporting and driving the screens and shaft as set forth.

4. An improved rotary screening apparatus having a plurality of compartments each consisting of screens of circular cross section mounted in alignment and provided with perforations of successively increasing size, a central shaft around which the screens are fixed, outer screens surrounding the screens having the smallest apertures and supported on said screens by means of distance pieces between these screens, and divided rings clamping the outer screens to the distance pieces, means for delivering the materials to be screened directly into the screens having the smallest perforations at one end of the compartments, and means for supporting and driving the screens and shaft as set forth.

5. An improved rotary screening apparatus having a plurality of compartments each consisting of screens of circular cross section mounted in alignment and provided with perforations of successively increasing size, a central shaft around which the screens are fixed, said central shaft being formed by a number of arcuate plates having their concave sides outwards, which are connected along their outer edges, outer screens surrounding the screens having the smallest apertures, distance pieces between the inner and the outer screens, divided rings clamping the outer screens on to the distance pieces, means for delivering the materials to be screened directly into the screens having the smallest perforations at one end of the compartments, and means for supporting and driving the screens and shaft as set forth.

6. An improved rotary screening appa-

5 ratus having a plurality of compartments each consisting of screens of circular cross section mounted in alignment and provided with perforations of successively increasing size, outer screens surrounding the said screens having the smallest apertures, distance pieces 10 between the inner and the outer screens, divided rings clamping the outer screens on to the distance pieces, a central shaft around which the screens are fixed, said central shaft being formed by a number of arcuate plates having their concave sides outwards, which are connected along their outer edges, strips of metal fixed between 15 the edges of each two adjacent plates, means for delivering the materials to be screened directly into the screens having the smallest perforations at one end of the compartments, and means for supporting and driving the 20 screens and shaft as set forth.

7. An improved rotary screening apparatus having a plurality of compartments each consisting of screens of circular cross section mounted in alignment and provided

25 with perforations of successively increasing size, outer screens surrounding the screens having the smallest apertures, distance pieces 30 between the inner and the outer screens, divided rings clamping the outer screens on to the distance pieces, a central shaft around which the screens are fixed, said central shaft being formed by a number of arcuate plates having their concave sides outwards, which are connected together along their outer edges, arcuate seatings attached to said arcuate plates and acting as seatings for the said screens, metal straps passing around portions 35 of the screens and bolted at their ends to the ends of the arcuate seatings, means for delivering the materials to be screened directly 40 into the screens having the smallest perforations at one end of the compartments, and means for supporting and driving the screens and shaft as set forth.

In witness whereof I have hereunto set 45 my hand.

JAMES WATT.
